Patented Feb. 22, 1966

203,855

COFFEE POT

Gerald Gulotta, 420 E. 72nd St., New York, N.Y.

Filed July 28, 1965, Ser. No. 86,337

Term of patent 14 years

(Cl. D44—26)

FIG. 1

FIG. 2

FIG. 6

FIG. 3

FIG. 4

I claim:

The ornamental design for coffee pot, substantially as shown.
